PHILADELPHIA, PENNSYLVANIA.

LATCH KNITTING-NEEDLE.

1,032,613.

Specification of Letters Patent. Patented July 16, 1912.

Application filed June 24, 1911. Serial No. 635,212.

To all whom it may concern:

Be it known that I, AUGUSTUS KORNDOERFER, Jr., a citizen of the United States, residing at Philadelphia, in the county of Philadelphia and State of Pennsylvania, have invented certain new and useful Improvements in Latch Knitting-Needles, of which the following is a specification.

This invention relates to knitting needles of the latch type, and has to do more particularly with a needle of that character in which the pivot for the latch is integral with the shank of the needle, as contradistinguished from those needles in which the pivot is set in and riveted to the shank.

The disadvantages resulting from the pivots of latch needles becoming loose is well known in the art and need not be herein set forth, and numerous attempts have been made heretofore to prevent the loosening of the riveted pivots, but at the present time no entirely satisfactory needle of this type has been introduced for the knitting industry.

The principal object of the present invention is to provide a knitting needle which overcomes the objections inherent in the set-in or riveted pivot needle, by employing an improved form of pivot and latch which can be readily assembled in place.

In carrying out the invention, I provide an elongated pivot in the chamber of the shank of the needle, which pivot is preferably integral with the side walls of the chamber. Attached to the pivot is a latch which has an enlarged pivot-receiving eye that is open or slotted at one point in its perimeter so that the pivot can be entered in the eye in assembling the latch, the slot being slightly wider than the transverse or minor axis of the pivot in order that the pivot can enter the eye diametrically. The slot in the eye is so arranged that it cannot move into alignment with the major axis of the pivot during the natural movement of the latch within its prescribed limits between open and closed position, and hence the latch can never become accidentally detached from the pivot after it is once properly assembled. Since the slot of the eye is located in a manner to secure these results, the latch, in the initial step of assembling, will be in an abnormal position, or one lying

outside the normal range of movement of the latch. After the latch is applied to the pivot, it is moved to its final position with the slot of the eye out of alignment with the major axis of the pivot.

For a more complete understanding of the invention, reference is to be had to the accompanying drawings, in which:

Figure 1 is a perspective view of the improved latch needle. Fig. 2 is a sectional perspective view through the pivot portion of the needle. Fig. 3 is a perspective view of the latch enlarged. Figs. 4 to 7, inclusive, are detail sectional views of the needle showing the manner of assembling the latch. Figs. 8 to 12, inclusive, are detail sectional views of another form of latch and the manner of assembling the same.

Similar reference characters are employed to designate corresponding parts throughout the views.

Referring to the drawing, 1 designates the shank of the needle, which has at one end the usual hook 2, at the base of which the shank is enlarged and provided with a chamber 3 for receiving the latch 4. Extending across the chamber is a pivot 5 which is integrally connected with the side walls 6 of the chamber, as clearly shown in Fig. 2, and surrounding this pivot is the eye 7 of the latch 4. This eye is somewhat larger than the eye of the latch of an ordinary needle and has an opening or slot 8 at a suitable point which is radial and of considerably less width than the diameter of the eye, for permitting the latch to be assembled when held in one position on the pivot and to be retained thereon when in open or closed or intermediate positions.

As more clearly shown in Figs. 4 to 12, inclusive, the pivot 5 is considerably widened or flattened; preferably, although not necessarily in the direction of length of the shank, the major or longitudinal axis of the pivot being substantially the same as the diameter of the eye. The slot 8 in the eye of the latch is slightly wider than the transverse or minor axis of the pivot in order to permit the pivot to be freely entered in the eye. As the pivot is of rectangular cross section, only its ends, and in fact the corners of the pivot afford bearings for the latch; and as the result, the latch has a four-point

contact with the pivot, so that friction is materially reduced and the latch can move back and forth freely.

In assembling the latch after the method depicted in Figs. 4 to 7, inclusive, the free or spoon end of the latch is left unfinished so that the latch can be inserted bodily into the chamber 3 of the shank, as shown in Fig. 4, the length of the chamber below the bottom of the pivot 5 being greater than the length of the latch for permitting of the ready insertion thereof. The initial position of the latch is shown in Fig. 4, where the slot or opening 8 of the eye is in alignment with and disposed under the lower end of the pivot. The latch is moved upwardly, as indicated by the arrow, in a line parallel with the major axis of the pivot to enter the pivot diametrically of the slot until the latch is in the position shown in Fig. 5. The latch is slightly rotated in the direction indicated by the arrow, in order to throw the slot 8 out of alignment with the pivot. This brings the tip of the latch out of the forward open side of the chamber 3, and it now merely remains to shape the tip of the latch into the usual spoon. The tip being thus spread, it cannot reenter the chamber and assume the position shown in Fig. 5, because the width of the chamber 3 is less than the width of the spoon tip of the latch. The latch is thus limited in its open position by the tip engaging with the shank of the needle, as shown in Fig. 6, and limited in its closed position by the tip of the latch engaging the bill of the hook 2, as shown in Fig. 7. The latch, in moving through its normal range of movement between open and closed position, does not bring its slot 8 into alignment with the longitudinal axis of the pivot, the slot remaining at all times to one side of such axis, and as a consequence, it is impossible for the latch to become detached from its pivot after the latch has been moved to and confined in its normal range of movement by the spoon being formed on the tip of the latch after the latter has been engaged with the pivot.

The construction shown in Figs. 9 to 12, inclusive, necessitates a different method of assembling the latch. It will be observed that the slot 8' of the eye of the latch is located near the medial portion thereof, and furthermore the spoon on the tip of the latch is completed before the latter is assembled. The latch is first positioned as shown in Fig. 8, with its slot 8' in alignment with the pivot and with its tip disposed between the shank of the needle and bill of the hook. The latch is raised vertically to enter the pivot into the eye, the tip of the latch passing under the bill of the hook, as clearly shown in Fig. 9. The tip of the latch is flexed to one side, it being understood that the latch is made of tempered steel or other

resilient metal, and while bent thus to one side, the tip is swung forwardly past the side of the bill of the hook, as clearly shown in Fig. 10. After the latch has reached a point in front of the bill, the lateral pressure is removed from the tip so that it can engage the front of the bill, as shown in Fig. 11, wherein the latch is in its closed position and the slot 8' of the eye out of alignment with the pivot 5. When the latch is in open position, as shown in Fig. 12, the slot 8' is also out of alignment with the pivot, so that it is impossible for the latch to become disconnected. In this form of latch, the slot is at all times at the front side of the pivot. In order to detach the latch, the steps are taken in the reverse order, from Figs. 11 to 8, inclusive.

From the foregoing, it will be seen that the method of constructing the pivot and latch and of assembling the parts is extremely simple and comparatively inexpensive, and as the pivot cannot become loose or burst form on the end as is common with the set-in rivet type of needle, the many disadvantages accompanying the use of this latter class of needles will be overcome. Besides avoiding the great loss to manufacturers from imperfect material resulting from defective needles, the present improvements will result in a considerable saving to the knitting manufacturer from the needles themselves, because the breakage of a latch, for instance, does not render the whole needle useless, since the broken latch can be removed and a new one substituted.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention, what I claim as new, is:—

1. A latch knitting needle comprising a chambered shank, a flattened pivot in the chamber, and a latch having a pivot eye provided with a slot through which the pivot enters the eye and so disposed as to be out of line with the major axis of the pivot throughout the range of movement of the latch between open and closed position.

2. A latch knitting needle comprising a chambered shank, a flattened pivot integral with the side walls of the chamber in the shank, and a latch having a pivot eye provided with a slot wide enough to permit the

5 pivot to enter the eye diametrically, said slot being so positioned as to lie always at one side of the major axis of the pivot throughout the range of movement of the latch.

10 3. A latch knitting needle comprising a shank, a latch pivot thereon, and a latch having a pivot-engaging eye of fixed form open in one part of its periphery for the free passage into said eye of said pivot in one position of the parts.

15 4. A latch knitting needle comprising a chambered shank, a pivot of non-circular cross-section arranged in the chamber and being in its major axis of greater dimension than in its minor axis, and a latch having an eye of approximately the same diameter as the major axis of the pivot whereby the latch has bearing contact only with the portions of the pivot at the ends of the major axis, said eye having a radial slot through which the pivot enters the eye diametrically and which is so disposed that the major axis of the pivot will be out of line with the said slot throughout the range of movement of the latch.

20 25 5. A latch knitting needle comprising a chambered shank, a pivot of rectangular

cross section in the chamber, and a latch having an eye of substantially the same diameter as the width of the pivot, said eye being provided with a slot of substantially the same width as the thickness of the pivot to permit the latter to be entered in the eye.

30 35 6. A latch knitting needle comprising a chambered shank, a pivot in the chamber, said pivot being of greater width than thickness and having its width extending longitudinally of the shank, and a latch having an eye provided with a slot through which the pivot is entered in the eye, the portion of the chamber below the pivot being of greater length than the length of the latch to permit the latter to be placed in position for assembling on the pivot, said latch having a widened tip for preventing the tip from entering the chamber to thereby maintain the slot out of alignment with the longitudinal axis of the pivot.

40 45 50 In testimony whereof I affix my signature in presence of two witnesses.
